2 Sheets—Sheet 2.

C. POTTER, Jr.

SHEET DELIVERY APPARATUS FOR PRINTING MACHINES.

No. 354,872.

Patented Dec. 21, 1886.

UNITED STATES PATENT OFFICE.

CHARLES POTTER, JR., OF PLAINFIELD, NEW JERSEY.

SHEET-DELIVERY APPARATUS FOR PRINTING-MACHINES.

SPECIFICATION forming part of Letters Patent No. 354,872, dated December 21, 1886.

Application filed March 29, 1886. Serial No. 196,892. (No model.)

To all whom it may concern:

Be it known that I, CHARLES POTTER, Jr., of Plainfield, in the county of Union and State of New Jersey, have invented an Improvement 5 in Sheet-Delivery Apparatus for Printing-Machines, of which the following is a specification.

Printing-presses have been made in which the impression-cylinder makes two revolutions to one impression, the printed sheet being carried away horizontally, or nearly so, during the following impression.

My present invention relates to an improvement in this class of presses; and it consists in 15 the combination, with the two-revolution impression-cylinder, of delivery-slats and belts to convey the sheets from the cylinder, a stop or fence to arrest the movement of the sheet, gripper-fingers and a traveling cross-bar, by 20 means of which the sheet is taken and laid upon the delivery-table, and a range of lifter-bars to raise the sheet up so as to be taken by the grippers.

In the drawings, Figure 1 is a side view 25 showing the general position of my improvements in relation to the frame of the press. Fig. 2 is a partial plan of the improved apparatus. Fig. 3 is a section longitudinally of the delivery devices. Fig. 4 is a partial cross- 30 section at the line $x-x$, Fig. 3; and Figs. 5, 6, and 7 represent devices that may be employed to give motion endwise of the press to the sheet-delivery gripper-bar.

The frame A of the press and the impression-cylinder B are of any known character, and the impression-cylinder is provided with the grippers and delivery-fingers, actuated alternately, as usual. Across in front of the impression-cylinder is the range of delivery-slats 2 2, supported by the stationary cross-bars 3 3. These slats are at an inclination, and after the paper has been printed the grippers a^2 are opened and the throw-off fingers a^3 lift the advancing end of the sheet above 45 the slats 2, and as the impression-cylinder makes its second revolution the sheet is slid down the slats 2 upon the range of tapes or belts 4, that pass around the pulleys 6 7, and by such tapes the sheet is carried along until 50 its advancing edge is arrested by the fence 8. The train of bevel-gearing and shafts 9 10 11

12 13 14 15 16 serve to drive the shaft of the pulleys 6 and the belts 4, and also the mechanism that actuates the cross-bar 20 and shaft 35, carrying the gripper-fingers 21 22. 55

Between and parallel with the belts 4 are the lifter-bars 25, connected with the head-pieces 26 on the rocker-shaft 27. These lifter-bars 25 lie upon the support 28, near the fence 8, and at the end or ends of the rocker-shaft 60 27 there is an arm, 30, and a connecting-rod, 31, with a roller, 32, resting upon the cam 33. This cam 33 is shaped and timed so that when the sheet has passed along upon the tapes 4 and reached the fence 8 the rocker-shaft is 65 partially turned and the sheet lifted bodily off the tapes, so as not to be blurred by the tapes if there is printing upon the under side, and the end of the sheet is brought directly into the path of the grippers 21 22 and seized by 70 them and drawn off the lifter-bars, after which the bars descend, ready to receive the next sheet.

The gripper-fingers 22 are upon a cross-shaft, 35, and they are closed by the spring 36; 75 and the arm 37, with a roller or stud at the end, is used to open the grippers by passing over the inclined switch 40, that is pivoted at its upper end. The grippers and cross-bar being moved bodily and lengthwise of the 80 press by any suitable means, the switch 40 opens the grippers as they approach the end of the sheet as it lies upon the lifter-bars, and the stud or roller 41, passing off the switch, allows the spring to close the grippers, and the 85 sheet is conveyed away by the cross-bar as it is moved. The switch 40, however, is raised by the stud on the gripper-arm as said stud underruns such switch, and when the gripper-bar reaches the end of its motion the grippers 90 are opened by the roller 41, upon the arm 37 having come into contact with the stationary incline 42.

The devices for carrying the gripper-bar back and forth bodily may be of any desired 95 character. I have shown the screw 50 passing through a nut, 51, at the end of the gripper-bar 20, it being understood that there are two screws, one at each side of the press, and that they receive motion from the gearing 52 100 53 and shaft of the pulleys 6. In this case it is necessary to revolve the train of gearing,

first one way and then the other, by connecting the same to the reciprocating bed of the press.

In Figs. 5, 6, and 7 a different device is shown for moving the cross-bar 20, shaft 35, and grippers. In this instance the said cross-bar and shaft are upon a shell, 70, at each end, and this shell 70 contains two bevel-gears, 53 56, one of which is upon a shaft, 58, that passes across to a similar shell upon the other side of the press, and there is a pair of gear-wheels, 54, gearing into rack-teeth 55 upon the frame of the machine. The other gear 56 is upon a feather and around the shaft 57, which corresponds to and is driven in the same manner as the screw 50; hence the shaft 57 will be rotated first one way and then the other, and as the wheels 54 roll back and forth over the stationary racks 55 the shells will be carried first one way and then the other, and the pinion 56 will be slipped along upon the feathered shaft, and the gripper-bar will be moved bodily, as aforesaid.

I remark that the sheet-delivery table 60 is below the grippers as they move back and forth, and upon that table the sheet falls as liberated from the grippers.

I claim as my invention—

1. The combination, with the impression-cylinder having grippers and throw-off fin-

gers, of the stationary inclined slats down which the sheet is passed, the conveying tapes or belts 4, the lifter-bars for raising the sheet off the belts, and the grippers for grasping and conveying away the sheet, substantially 35 as set forth.

2. The combination, with the impression-cylinder, of the delivery tapes or belts, the lifter-bars between such belts, the rocker-shaft to which such lifters are connected, the 40 arm and cam for moving the rocker-shaft, a fence to arrest the movement of the sheet, gripper-fingers, and a shaft and bar and mechanism, substantially as set forth, for moving the gripper-bar and carrying the sheet to the 45 delivery-table, substantially as set forth.

3. The combination, with the delivery-belts and pulleys, of the lifting-bars, the rocker-shaft, the fence, the gripper-bar and grippers and mechanism for giving motion to the same, 50 the switch for opening the grippers and then allowing them to close and seize the sheet, and the incline for opening the grippers and delivering the sheet, substantially as set forth.

Signed by me this 23d day of March, A. D. 55 1886.

CHARLES POTTER, JR.
